UNITED STATES PATENT OFFICE.

ROBERT STUART, OF PHILADELPHIA, PENNSYLVANIA.

WINDOW FASTENER AND ANTIRATTLER.

Application filed August 1, 1922. Serial No. 578,877.

To all whom it may concern:

Be it known that I, ROBERT STUART, a citizen of the United States, residing at Philadelphia, county of Philadelphia, State of Pennsylvania, have invented a new and useful Window Fastener and Antirattler, of which the following is a specification.

My invention comprehends a novel construction and arrangement of a window fastener which causes the sash to always be drawn inwardly toward the window frame in order to prevent any rattling and also to prevent admission of cold air in winter, and wherein means are provided for locking the sash in order to limit the amount of its opening movement.

It further comprehends a novel window fastener provided with a spring actuated roller which bears against the window frame, novel guiding means and a novel construction and arrangement of locking mechanism.

Other novel features of construction and advantage will hereinafter more clearly appear in the detailed description.

For the purpose of illustrating my invention, I have shown in the accompanying drawings a typical embodiment which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents, in perspective, a window in conjunction with which window fasteners embodying my invention are employed.

Figure 2 represents a top plan view of my device, the window being shown in section.

Figure 3 represents an end elevation on an enlarged scale of the window fastener in position.

Figure 4 represents a section on line 4—4 of Figure 3.

Figure 5 represents, in side elevation, a portion of the mechanism.

Figure 6 represents a section on line 6—6 of Figure 3.

Figure 7 represents in front elevation and on an enlarged scale the keeper of the locking mechanism.

Similar numerals of reference indicate corresponding parts.

Referring to the drawings, 1 designates the casing of a window fastener, embodying my invention, the casing being provided with base flanges through which extend fastening devices 2 in order to secure it in position with respect to the window sash 3.

The casing 1 is preferably formed from sheet metal or from a casting and has secured within it preferably by means of a driving fit the sleeve 4 to which is connected in any desired manner a centrally located tube 5 within which is contained the spring 6. The spring 6 abuts against the inner wall of the casing 1 and against the head 7 of a screw 8 the shank of which is freely slideable through an opening 9 in the casing 1 and is secured at 10 to a guide member 11 which is provided with the legs 12 which pass through the slot 26 in the top wall of the casing 1, which latter is otherwise closed. The guide member 11 has connected with it a post 13 having a series of apertures 14 near one end adapted to receive the screw 15 which carries the roller 16, a bushing 17 being preferably interposed between the rounded shank of the screw 15 and the roller 16.

The casing 1 has pivoted to it at 18 a locking lever 19 which on one side is provided with the raised portion 20. The operative end 21 of the lever 19 is adapted to contact with a stop member 22 of a keeper 23 which latter is provided with apertures 24 adapted to receive fastening devices 25 by means of which the keeper is secured in proper position with respect to the window frame. The keeper 23 is preferably formed from a piece of sheet metal having portions deflected therefrom to form the stop member 22.

The operation of my novel window fastener will now be apparent to those skilled in the art to which this invention appertains and is as follows:

One or more window fasteners may be employed for each sash. The roller 16 rides on the jamb of the window frame and owing to the provision of the spring 6 the sash is resiliently moved inwardly so that at all times a working fit is provided which will prevent any rattling and which will form practically an air tight joint. The roller fastening device 15 is secured in the proper aperture 14 to give the desired result.

- When it is desired to lock the window to limit its opening the lever 19 is swung from the position seen in full lines in Figure 2 to that seen in dotted lines in said figure so that 5 the locking end 21 will be in the path of a stop member 22 so that the window cannot be opened except to a limited extent. It will be seen that the locking lever 19 is provided with a raised portion 20 which will prevent 10 the inward movement of the lever 19 beyond the position seen in dotted lines in Figure 2 when this raised portion engages a stop member 22.
- The stop members 22 may be spaced apart 15 any desired distance. My present invention does not interfere with the ordinary or regular lock and provides an additional locking member so that the window sash or window sashes can only be opened to a desired limited degree and, if desired, the stop members 22 may be arranged close enough together to prevent any upward or downward movement of a window sash when the locking lever 19 is in locking position.
- 20 It will be apparent that I have devised a novel and useful window fastener which embodies the features of advantage enumerated as desirable in the statement of the invention and the above description, and while 25 I have, in the present instance, shown and described a preferred embodiment thereof which will give in practice satisfactory and reliable results, it is to be understood that this embodiment is susceptible of modification 30 in various particulars without departing from the spirit or scope of the invention or sacrificing any of its advantages.
- Having thus described my invention, what I claim as new and desire to secure by Letters Patent, is:
1. A window fastener and anti-rattler, comprising a casing adapted to be secured to the window sash, a roller adapted to travel on the window jamb, a roller support 45 having a plurality of guides slidable in said casing, resilient means to cause said roller to draw said sash towards said jamb and a locking member movably carried by said casing.
  2. A window fastener and anti rattler, comprising a casing adapted to be secured to a window sash, a roller adapted to travel on the window frame, a roller support slid- 50 able in said casing, resilient means to cause the roller to draw said sash towards said
- frame, a keeper secured to said frame and having stop members; and a locking member movably carried by said casing and adapted to contact with one of said stop members to limit the opening movement permitted of the window sash.
3. A window fastener and anti-rattler, comprising a casing adapted to be secured to a window sash, a roller adapted to travel on the window frame, a roller support 65 guided by said casing, resilient means to cause the roller to draw said sash towards said frame, a keeper secured to said frame and having a stop member, and a locking member movably carried by said casing and adapted to contact with said stop member to limit the opening movement permitted of the window sash, said locking member having a portion to engage said stop member to thereby limit its movement in one direction.
4. A window fastener and anti-rattler, comprising a casing, a tube within said casing, a fastening device having its head guided in said tube, a sleeve within said casing, a guide member having legs slidable 70 in said casing and having a screw, the head of which is slidable in said sleeve and the shank of which is connected with said fastening device, a spring between the head of said fastening device and said casing, a post secured to said guide member, a roller carried by said post, said casing being adapted to be secured to a window sash and said roller to travel on the window jamb whereby said spring causes said shaft to be moved 75 inwardly toward said jamb, and a window locking member pivoted to said casing.
5. A window fastener and anti-rattler, comprising a casing having a slot and adapted to be secured to a window sash, a sleeve within said casing, a tube connected with said sleeve, a spring within said sleeve, a guide member having legs slidable in said slot and having means against which said spring bears to move said legs into said 80 casing, a post connected with said guide member and having a plurality of apertures, a screw secured in one of said apertures, a roller carried by said screw, and a window locking member pivoted to said casing.

ROBERT STUART.
